FEEDING MECHANISM

Ernst C. Sauerman, Chicago, Ill.

Application July 3, 1936, Serial No. 88,749

5 Claims. (Cl. 164—42)

This invention relates to improvements in a machine for delivering transparent sheets to an envelope machine for making envelopes of the "window" type, and refers specifically to a relatively simple device for feeding, cutting and delivering transparent sheets to the envelope machine *per se*.

Devices have heretofore been devised for feeding transparent sheets to a window envelope machine. However, these devices are characterized by their complexity and their inability to handle certain types of transparent materials, or more strictly speaking, they operate satisfactorily only on materials which possess certain predetermined characteristics. Many other materials are suited, and even more adaptable for use as window portions of window envelopes than those materials which can be used upon the prior art machines, but due to the inability of such machines to satisfactorily handle these materials they cannot feasibly be used.

More specifically the machines of the prior art are characterized in that they constantly feed a strip of transparent material forwardly to a cutting zone wherein individual window sheets are cut therefrom. The cutting operation in its very nature, however, is an intermittent operation and hence the constantly fed strip buckles during the cutting period. Subsequent feeding to the cutting zone of a predetermined length of strip is thereby dependent upon the resiliency of the material and the ability of the buckled portion to straighten or spring outwardly into the path of the cutting knife. Consequently, only those materials can be feasibly used which possess this inherent ability to spring outwardly. Many materials suitable for envelope windows do not possess this quality and cannot be used. Others possess it during ideal conditions of humidity and temperature but are not suitable during other atmospheric conditions. Hence, the range of selection of materials for envelope windows has heretofore been seriously limited.

My invention is characterized in that it handles with equal facility all available types of transparent materials which are suitable for envelope windows and even handles such materials with less difficulty than machines heretofore used can handle their ideal material.

Other objects and advantages of my invention will be apparent from the accompanying drawings and following detailed description.

In the drawings, Fig. 1 is a top plan view of my improved feeding device.

Fig. 2 is a sectional view taken on line 2—2 of

Fig. 1, illustrating the feed device cooperatively disposed with the usual uniting and folding machine.

Fig. 3 is a fragmentary plan view of a window envelope with adhesively united window. 5

Fig. 4 is a fragmentary sectional view taken on line 4—4 of Fig. 1.

Fig. 5 is a similar view illustrating a different phase of cam position.

Fig. 6 is a sectional view taken on line 6—6 of Fig. 1. 10

Fig. 7 is an end elevational view of the swing shaft cam.

Fig. 8 is a sectional view taken on line 8—8 of Fig. 1. 15

In the manufacture of envelopes commonly referred to as window type envelopes such as illustrated at 1, Fig. 3, an aperture 2 is provided in the face of the envelope and at the rear of said aperture, that is, the interior face of the envelope, a transparent sheet 3 is adhesively united, the transparent sheet serving as the window permitting inscribed matter within the envelope to be read or discerned from the exterior thereof. The materials suitable for envelope windows comprise substantially any relatively flexible transparent sheet material. However, due to certain imperfections in machines heretofore used to manufacture such envelopes, particularly that portion of the machine which feeds the transparent sheet material, only several grades of waxed paper or Glassine could be commercially used and still maintain the cost of the envelope within competitive limits. It is admitted by the art that transparent cellulosic material such as Cellophane makes a decidedly superior window but extreme difficulty has heretofore been encountered in handling such materials on machines heretofore available. 25 30 35

Broadly speaking, one of the most popular and widely used types of envelope machines for making window envelopes comprises a folding unit 4 and a feeding unit 5. My invention is particularly concerned with the feeding unit 5 which may be used with a conventional folding unit illustrated at 4. 40 45

The unit 4 comprises a platform 6 which may be mounted upon a suitable support 7. The platform 6 is provided with an opening 8 intermediate its area in which a plate 9 is disposed during the envelope folding operation. The plate 9 is carried upon an arm 10 which is pivoted at one end, as at 11, to lug 12 comprising a portion of the frame of the machine. A rod 13 is pivotally 50 55

connected to the arm 10 as at 14. The operation of the arm 10 and plate 9 is as follows:

During the folding operation of the envelope the plate 9 is disposed in a plane parallel to the platform 6. After the envelope has been partially folded, rod 13 acts to swing the plate 9 downwardly about the pivot point 11, the rod 13 being actuated by a suitable cam or eccentric mechanism (not shown). When the plate is thus swung downwardly, an envelope which is carried by said plate is discharged to suitable conveying means (not shown).

A compartment 15 is provided immediately above the plate 9 and is defined by side walls 16 and end walls 17 which are disposed in substantially vertical alignment with the edges of the plate 9. A superstructure 18 is positioned above the compartment 15 and serves as a guide for a vertically reciprocating plunger rod 19. A plunger 20 is mounted at the lower end of the rod 19, said plunger conforming with the horizontal sectional contour of the compartment 15 and being of slightly lesser dimensions whereby said plunger may be reciprocated within the compartment. One portion of the lower face of the plunger 20 is apertured, said apertures connecting with a source of vacuum (not shown).

In operation of the folding mechanism 4 envelope blanks 21 are positioned over compartment 15 in timed relationship with the movement of the plunger 20. A sheet of transparent material 3 is delivered by a feeding means to the lower face of the plunger 20, said sheet being retained upon the lower face of the plunger by means of the vacuum established through the apertures provided in said lower face. The blank 21 has previously been supplied with a quantity of adhesive adjacent the aperture 2. Consequently, upon downward motion of the plunger 20 the sheet carried upon the lower face of the plunger is brought into contact with that portion of the envelope 1 which is adapted to carry the window 3. As the plunger 20 descends into the compartment 15 the flaps 22 and 23 of the envelope are folded by the cooperative action of the compartment walls and the plunger. When the plunger 20 has descended to its maximum depth within compartment 15, the face of the envelope is pressed between the plunger 20 and the plate 9 and the transparent sheet 3 is securely united over the aperture 2. Subsequently, the plunger is lifted and simultaneously the plate 9 swings downwardly to deliver the folded envelope to a suitable conveying means.

The mechanism hereinabove described is conventional and forms no part of my present invention. As hereinbefore pointed out my invention is concerned particularly with the mechanism 5 which cooperates with the conventional mechanism 4 and will hereinafter be more fully described.

The feeding unit 5 comprises essentially a suitably timed feeding and cutting mechanism which is carried by oppositely disposed supports 24 which may be mounted upon a base plate 25. The foundation plate 25, in turn, may be positioned upon platform 6 adjacent the folding mechanism 4. The spaced supports 24 carry at their upper ends a plurality of parallel shafts 26, 27, 28, 29, 30 and 31 which are journaled in suitable bearings mounted in the upper portion of said supports. Shaft 26 comprises the drive shaft for the mechanism and may itself be driven from any suitable source of power. Of course, shaft 26

must be driven in timed relationship with the operation of the plunger 20 in the unit 4.

Referring particularly to Figs. 1 and 6, an intermittent gear 32 is mounted adjacent one end of shaft 26, said gear being rigidly secured to said shaft by means of set screw 33. The gear 32 is provided with teeth 34 formed upon a predetermined degree of arc of the periphery of the gear. The remaining portion of the arc is blank and comprises the pitch circuit of the teeth 34. A gear 35 is mounted upon shaft 27 and is rigidly secured thereon by means of set screw 36. The gear 35 is provided with two arcuately spaced sets of teeth 37 and 38, each of which correspond in arc length and number of teeth with the teeth 34 on the gear 32. Those portions of the gear 35 intermediate the sets 37 and 38 are blank and are arcuately shaped with a radius of curvature equal to that of the pitch circle of the gear 32.

The operation is such that when the gear 32 is rotated upon shaft 26 the gear teeth 34 alternately engage the sets of gear teeth 37 and 38 thereby intermittently rotating the gear 35 and, hence, shaft 27.

Shaft 27 carries a draw roll 39 upon its intermediate portion, the surface of said roll being preferably of soft rubber or other relatively resilient material. Adjacent the opposite end of shaft 27 a spur gear 40 is mounted which meshes with a spur gear 41 carried upon a shaft 28, said spur gears being in 1 to 1 ratio. Draw roll 42 is mounted intermediate the length of the shaft 28 and is disposed in osculating relationship with the draw roll 39. A shaft 29 is disposed adjacent shaft 28 and carries a pair of arms 43. The outer ends of each of the arms 43 comprise bearings in which the shaft 28 is journaled. An arm 44 is rigidly secured to shaft 29 and is connected at its outermost end by means of coil spring 45 to a portion of the frame of the machine. It can readily be seen, that by this arrangement the shaft 28 is in a substantially floating condition and is resiliently impelled, by means of spring 45, toward shaft 27. In this manner the surfaces of the draw rolls 39 and 42 are urged together under the influence of spring 45.

A web 46 from which the window sheets 3 are cut is fed between the draw rolls 39 and 42. Due to the intermittent operation of the rolls 39 and 42, the web 46 is intermittently delivered from between said rolls and is discharged upon an inclined metal platform 47 mounted upon a metal support 48 which, in turn, is mounted upon, and grounded upon the frame of the machine. The web 46 delivered over platform 47 is deflected downwardly on the end of said platform by means of the guide plate 49. A block 50 is secured to the support 48 by means of screws or the like 51, the arrangement being such that block 50 is adjustable to a limited degree in a direction parallel to the support 48. The block 50 carries a cutting member 52 which is removably positioned upon said block by any suitable means.

A cam 53 is mounted upon the end of shaft 26 and is rigidly secured thereon by means of set screw 54. A rocker arm 55 is secured by means of set screw 56 to shaft 31. At one end of arm 55 a follower roller 57 is carried and the opposite end of said arm is resiliently anchored to the frame of the machine by means of coil spring 58, said spring acting to maintain the follower roller 57 in contact with the peripheral surface of cam 53.

Referring particularly to Figs. 1 and 2, spaced arms 73 are rigidly secured to shaft 31, said arms 73

carrying between their outer ends a hollow swing member 74, one face of which is provided with a plurality of apertures 75 which connect with the hollow interior of the member 74.

5. A cam 67 is rigidly mounted upon an intermediate portion of drive shaft 26. An arm 68 is mounted upon a corresponding portion of the shaft 30, said arm being secured thereon by means of set screw 69, and the end of said arm carries 10 a follower roller 70 which is adapted to ride upon the peripheral surface of the cam 67. Arm 71 is also secured to shaft 30 and is resiliently anchored to a portion of the frame of the machine by means of coil spring 72, said spring acting to 15 maintain the follower roller 70 in contact with cam 67.

A plurality of spaced bosses 59 are formed upon a sleeve 60 which, in turn, is rigidly mounted upon shaft 30. An elongated screw 61 is threadedly 20 engaged in each of the bosses 59. A sleeve 62 embraces a portion of the shank of each screw 61 and serves to space cutter blade 63 at a desired position from the axes of rotation of shaft 30. The cutter blade 63 is provided with apertures 64 through which screws 61 pass and a coil spring 25 65 is confined between the head 66 of each screw and the blade 63.

The arrangement is such that when a predetermined length of the web 46 is fed from between rolls 39 and 42, said length being determined by the gear ratio of the intermittent gears 32 and 35, cam 67 acts to rock shaft 30 thereby swinging blade 63 in a counterclockwise direction as viewed in Fig. 2. As can readily be seen in Fig. 2 35 in dotted lines, the blade 63 is so swung by shaft 30 as to pass adjacent the cutting member 52 carried by the block 50. The guide 49 during the feeding of the web 46 deflects a predetermined length of said web adjacent the cutting member 52 and, 40 consequently, said web is sheared by the passage of the cutter blade 63. As will be hereinafter more fully described, at predetermined portions of movement of the shaft 31 a condition of vacuum is established within the hollow interior of the member 74. Just prior to the feeding of a 45 predetermined length of the material 46 over the block 50, shaft 31 has been rocked so as to bring arm 73 and the swing member 74 into the position shown in dotted lines in Fig. 2. Therefore, the portion of the web 46 which has been deflected 50 downwardly by the guide 49 passes over the face of the swing member 74. When this phase of movement has been reached shaft 30 moves to cut or shear the projected portion of the web 46 55 leaving the cut sheet 3 upon the face of the swing member 74. As will be hereinafter more fully described, a condition of vacuum is established within the swing member just prior to the severances of the sheet 46 and, consequently, said severed sheet is caused to adhere to the surface of the swing member 74.

A cam 76 is rigidly mounted upon an intermediate portion of shaft 26 and a block 77 is mounted upon the frame of the machine adjacent 60 the path of travel of the cam 76. The block 77 is provided with a central recess 78 in which a cylindrical barrel 79 is rotatably positioned. The block 77 is provided with bores 80 and 81 which connect into the central aperture 78. The 65 barrel 79 is provided with a connecting bore 82 which traverses the diameter of the barrel. A pipe 83 connects into block 77 making connection with the bore 80 and a pipe 84 connects with the opposite bore 81. A flexible conduit 85 connects 70 pipe 84 to pipe 86 which, in turn, connects into 75

the interior of the hollow swing member 74. The pipe 83 connects to a source of reduced pressure or vacuum (not shown) and depending upon the position of the barrel 79, periodically connects the interior of the swing member 74 to said source of 5 vacuum thereby establishing a condition of vacuum within the hollow interior of the swing member. A plate 87 is rigidly secured to the barrel 79 and carries on its face an eccentrically mounted roller 88. A coil spring 89 anchors pin 90 carried 10 upon the face of plate 87 to a portion of the frame of the machine whereby the roller 88 is normally maintained in contact with the peripheral surface of the cam 76. A relatively small opening 91 is provided in the face of the plate 87 and connects 15 with a registering opening in block 77 which opening in turn connects with the bore 81. The aperture 91 registers with and connects with the bore 81 only when barrel 79 has rotated to a predetermined position disconnecting bores 80 20 and 81.

In operation when the cutter blade 63 acts to sever the projected strip positioned adjacent the face of the swing member 74, roller 88 carried upon plate 87 passes to the low portion of the 25 cam 76 thereby swinging barrel 79 into the position illustrated in Fig. 5. In this position communication is established by the bores 80 and 81 and a condition of vacuum is established within the swing member 74. Due to the provision of 30 the apertures 75 in the face of the swing member, the severed strip 3 is caused to adhere to the face of the swing member. Shaft 31 is then caused to rotate by means of the engagement of the high portion of cam 53 and roller 57 and the swing 35 member is thereby caused to rotate in a clockwise direction as viewed in Fig. 2, to a position shown in full lines. In this position the face of the swing member is disposed adjacent the lower surface of the plunger 20 bringing the sheet 3 into 40 proximity with the apertures in the face of the plunger 20. When the swing member arrives at this position the roller 88 climbs to the high portion of cam 76, thereby rocking the barrel 79 to disconnect conduits 80 and 81. This movement 45 of the plate 87 brings aperture 91 into connection with the conduit 81 thereby connecting said conduit to the atmosphere and breaking the vacuum within the swing member 74. Simultaneously a 50 condition of vacuum is established by well known means within the plunger 20 and the sheet 3 is thereby transferred from the surface of the swing member to the lower surface of the plunger. The remaining operation is carried out by the unit 4 and has been hereinbefore described. 55

By the provision of my novel feeding and severing mechanism substantially any type of material suitable for windows in window envelopes may be used irrespective, within limits, of the thickness, resiliency or pliability of the material. 60 The operation carried out by the machine is simple and direct and the machine itself contains a minimum of movable parts.

I claim as my invention:

1. In an envelope machine for making window 65 envelopes having means for adhesively uniting transparent sheets over apertures provided in envelope blanks, a frame, means mounted on said frame for intermittently feeding a predetermined length of a web of transparent material 70 forwardly comprising a pair of intermittently operated draw rolls, means carried by said frame and operatively associated in timed relationship with said feeding means for severing said predetermined length of transparent material from 75

5 said web into a sheet at the end of said intermittent feed period, and means operated in timed relationship with said intermittent feeding means for carrying said severed sheet of transparent material to the adhesive uniting means, 10 said means comprising a shaft, a carrier member mounted upon said shaft and cam means operatively connecting said feeding means and shaft to rock said shaft and swing said carrier member to move the severed sheet to the adhesive uniting means.

15 2. In an envelope machine for making window envelopes having means for adhesively uniting transparent sheets over apertures provided in envelope blanks, a frame, a continuously rotating drive shaft journalled in said frame, a pair of juxtaposed draw rolls journalled in said frame, intermittent gears operatively connecting said drive shaft and draw rolls whereby a web of 20 transparent material is intermittently fed forwardly by said draw rolls, another shaft journalled in said frame, a cutting member carried by said last mentioned shaft, cam means operatively connecting said continuously rotating drive shaft and last mentioned shaft to rock 25 said latter shaft and move said cutting member to sever said transparent material, and means operated in timed relationship with said drive shaft for carrying said severed sheet of transparent material to the adhesive uniting means.

30 3. In an envelope machine for making window envelopes having means for adhesively uniting transparent sheets over apertures provided in envelope blanks, a frame, a continuously rotating drive shaft journalled in said frame, a pair of juxtaposed draw rolls journalled in said frame, intermittent gears operatively connecting said drive shaft and draw rolls whereby a web of 35 transparent material is intermittently fed forwardly by said draw rolls, another shaft journalled in said frame, a cutting member carried by said last mentioned shaft, cam means operatively connecting said drive shaft and last mentioned shaft to rock said latter shaft and move 40 said cutting member to sever said transparent material, said means comprising a carrier shaft journalled in said frame, a carrier member 45

5 mounted upon said carrier shaft, and cam means operatively connecting said drive shaft and carrier shaft to rock said latter shaft and swing said carrier member to move the severed sheet to the adhesive uniting means.

4. In an envelope machine for making window envelopes having means for adhesively uniting transparent sheets over apertures provided in envelope blanks, a frame, a continuously rotating drive shaft journalled in said frame, a pair of 10 juxtaposed draw rolls journalled in said frame, intermittent gears operatively connecting said continuously rotating drive shaft and draw rolls whereby a web of transparent material is intermittently fed forwardly by said draw rolls, means 15 carried by said frame and operatively associated in timed relationship with said drive shaft for severing a predetermined length of transparent material from said web into a sheet after said web has stopped its forward movement, a carrier shaft journalled in said frame, a carrier member mounted upon said shaft, and cam means operatively connecting said drive shaft and carrier shaft to rock said latter shaft and swing said carrier member to move the severed 20 sheet to the adhesive uniting means.

25 5. In an envelope machine for making window envelopes having means for adhesively uniting transparent sheets over apertures provided in envelope blanks, a frame, means mounted on said 30 frame for intermittently feeding a predetermined length of a web of transparent material forwardly comprising a pair of intermittently rotated draw rolls, a shaft journalled in said frame, a cutting member carried by said shaft, cam means 35 operatively connecting said shaft to said feeding means to rock said shaft and move said cutting member to sever said transparent material after rotation of said draw rolls has stopped, a carrier shaft journalled in said frame, a carrier member mounted upon said carrier shaft, and cam means operatively connecting said feeding means and carrier shaft to rock said carrier shaft and swing said carrier member to move the severed sheet to the adhesive uniting means.

45 ERNST C. SAUERMAN.
